Henry Brehmer INVENTOR

UNITED STATES PATENT OFFICE.

HENRY BREHMER, OF NEW YORK, N. Y., ASSIGNOR TO DAVID WOLFE BRUCE, OF SAME PLACE.

DESIGN FOR A FONT OF PRINTING-TYPE.

SPECIFICATION forming part of Design No. 19,675, dated March 4, 1890.

Application filed January 8, 1890. Serial No. 336,324. Term of patent 14 years.

To all whom it may concern:

Be it known that I, HENRY BREHMER, a citizen of the United States, residing at New York in the county and State of New York, (assignor to DAVID WOLFE BRUCE,) have invented a new and original Design for a Font of Printing-Types, of which the following is a specification, reference being had to the accompanying typographic impressions, forming part thereof.

Those typographic impressions are exact representations of the design, in which are comprised capital letters, punctuation-points, numerals, and the dollar and pound-sterling symbols, and its nature is fully shown therein.

This design is in form what is known as "old style," and its characteristic features are the grotesquely-shortened central angles in the M and W, the equivalent "shortness in

waist," as it were, of the A, B, E, F, H, K, P, R, X, and Y, and the connection of the angle at the top of the A through its short diagonal line, which line also tops the commencement of the tails of the K and R. The punctuation-points, numerals, and the dollar and pound-sterling symbols are all drawn in keeping with the capital letters, and the whole is of rather light weight.

What I claim as my invention, and desire to secure by Letters Patent, is—

The design for a font of printing-type, as herein described, and shown in the accompanying typographic impressions.

HENRY BREHMER.
